UNITED STATES PATENT OFFICE.

JOHN HORSFIELD, OF CHICAGO, ILLINOIS, ASSIGNOR OF ONE-HALF TO FRANK M. STRESEN-
RENTER, OF CHICAGO, ILLINOIS.

CONCRETE-WALL MOLD.

No. 884,784.

Specification of Letters Patent.

Patented April 14, 1908.

Application filed August 22, 1907. Serial No. 389,648.

To all whom it may concern:

Be it known that I, JOHN HORSFIELD, a citizen of the United States of America, and a resident of Chicago, in the county of Cook and State of Illinois, have invented certain new and useful Improvements in Concrete-Wall Molds, of which the following is a specification.

This invention relates to an improvement in the type of molds for concrete walls which constitute the subject matter of my former application for Letters Patent Serial Number 381,407, filed June 29th, 1907; and has for its object to provide a simple and efficient structural formation and combination of parts in tie plates adapted to secure the intersecting corners of the mold planks together in a substantial and readily detachable manner, all as will hereinafter more fully appear.

In the accompanying drawings:—Figure 1, is a detail plan view of a corner portion of a mold for concrete walls, embodying the present invention. Fig. 2, is a detail vertical section on line $x-x$ Fig. 1. Figs. 3 and 4, are plan views of the blanks from which the tie plates are formed.

Similar numerals of reference indicate like parts in the different views.

Referring to the drawings, 1 and 2 are intersecting ends of pairs of mold planks arranged in separated relation to form the vertical walls of the mold cavity.

3 are the tie plates by which the mold planks are secured in proper vertical alignment. Such tie plates are formed of plate metal, so that when in place they will occupy but little vertical space between adjacent edges of the mold planks, and as usual in the present type of wall molds. In the present construction, said tie plates are formed at their inner ends with right angle flanges 4 and 5 extending in opposite directions away

from the main body of the plate and adapted to form stops for the adjacent inner corners of the mold planks to hold the same against inward lateral displacement. At their outer ends, said plates are formed with two or more elongated slots 6 for the passage of the tapering keys or wedges 7, which are driven into said slots and have bearing against the outer faces of the mold planks 1, and are adapted to force and clamp said mold planks against the flanges 4 and 5 as said keys or wedges are driven into place.

The novelty of the present improvement comprises two series of the above described flanges 4 and 5 on each tie plate and arranged in angular relation to each other, so that one series will be individual to one pair of mold planks, and the other series individual to the other and intersecting pair of mold planks; and in connection with the above described arrangement there will be a corresponding angular arrangement of the elongated slots 6 in the tie plate, so as to attain a corresponding individual relation of said slots and their tapering keys or wedges to the respective pairs of mold planks.

Having thus fully described my said invention, what I claim as new and desire to secure by Letters Patent, is:—

A tie plate for mold planks, comprising a main plate, having pairs of right angle flanges arranged in angular relation at one side of said main plate, and a pair of elongated slots in like angular relation at the other side of said main plate, and tapering keys engaging said slots, substantially as set forth.

Signed at Chicago, Illinois, this 19th day of August 1907.

JOHN HORSFIELD.
